DESIGN FOR A BOTTLE

Joseph B. Platt, New York, N. Y., assignor to Pond's Extract Company, New York, N. Y., a corporation of Delaware

Application May 23, 1947, Serial No. 139,247

Term of patent 7 years

(Cl. D58—6)

To all whom it may concern:

Be it known that I, Joseph B. Platt, a citizen of the United States, residing at New York, in the county of New York, and State of New York, have invented a new, original, and ornamental Design for Bottles, of which the following is a specification, reference being had to the accompanying drawing, forming part thereof.

In said drawing:

The essential features of my design reside in the portions shown in full lines.

I claim:

The ornamental design for a bottle, substantially as shown and described.

JOSEPH B. PLATT.
